UNITED STATES PATENT OFFICE.

FRANZ HAMMERLE, OF CAMBRIDGE, MASSACHUSETTS.

PEDAL-ACTION FOR PIANOS.

SPECIFICATION forming part of Letters Patent No. 447,319, dated March 3, 1891.

Application filed October 6, 1890. Serial No. 367,180. (No model.)

To all whom it may concern:

Be it known that I, FRANZ HAMMERLE, of Cambridge, in the county of Middlesex, State of Massachusetts, have invented certain new and useful Improvements in Pedal-Actions for Pianos, of which the following is a description sufficiently full, clear, and exact to enable any person skilled in the art or science to which said invention appertains to make and use the same, reference being had to the accompanying drawings, forming part of this specification, in which—

Figure 1 is a perspective view of an upright piano, the case being broken away to show my improved attachment; Fig. 2, a front elevation of the hammer-action mechanism; and Fig. 3, an end elevation of the same, partly in section.

Like letters and figures of reference indicate corresponding parts in the different figures of the drawings.

My invention relates especially to the "middle" or tone-sustaining pedal-action for upright piano-fortes; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation:

In the drawings, A represents the piano-case, B the action-frame, and C the hammer-action considered as a whole. These parts being of the ordinary construction and arrangement, it is not deemed essential to particularly describe the same herein. The damper-levers *b* are bent slightly at an obtuse angle, and are pivoted vertically at such point in ears *d* on a cross-bar *f*, secured in the side bars of the frame *B* below the pivot *g* of the ordinary hammers *D*. These levers are preferably constructed of wood, and from the upper end of each a vertical wire rod *h* projects, to the top of which the felt-faced damper-head *i* is secured. A flat spring *k*, secured to the pivot and bearing against the upper end of the lever *b*, tends to hold the head *i* in engagement with the piano-strings in the usual manner. A wire *m* is pendent from the lower end of each lever *b*, and is bent eccentrically or curved outwardly toward the case-front, form-

ing a head *p*. A horizontal crank-rod *t* is pivoted in the sides *v* of the action-frame below the damper-levers. Two arms *w* project at right angles from said rod in lines non-radial to the arc which the crank-arms describe. The arms *w* are connected at their outer ends by a felt-covered wire *x*. The arc through which said wire passes when moved crosses the arc of the heads *p* of the damper-wires at such point that it will not engage the damper-wires when in their normal position. On one of the pivots of the rod *t*, outside the frame *v*, a lever *z* is mounted, said lever resting on a pin 15 in the frame, against which it is held by a spring 16 engaging a similar pin 17, tending to hold the wire *x* out of engagement with the damper-wires. The pedal 25 (see Fig. 1) is mounted between the ordinary pedals 26 and 27 of the piano and actuates a horizontally-pivoted lever 28, disposed under the keyboard. On the end of said lever a vertical rod 29 is mounted, its upper end engaging the lever *z* and elevating it against the force of the spring 16 when said pedal is depressed.

In use when a key 30 is struck its rod 31, elevating the forward end of the hammer-lever 32 of the action, throws the rod 33 thereon against the lower end of the corresponding damper-lever *b*, moving its head *i* out of contact with the piano-strings and permitting them to vibrate when struck by the hammer in the usual manner. The pivot of the damper-levers *b* and the crank-rod *t* being in parallel vertical planes, as shown, when said levers are moved, as described, their wire heads *p* move inside or across the arc of the circle through which the rod or wire *x* will pass into the position represented by dotted lines in Fig. 3.

To sustain the tones of the notes struck and prevent their springs *k* from returning the dampers when the keys are released, the middle pedal 25 is depressed, throwing upward the bar 29 against the lever *z*. This elevates said lever, moving the crank *t* and throwing the felt-covered wire *x* against the heads *p* of the damper-wires, holding said dampers in the position assumed. When the pedal is released, the spring 16 throws the lever *z* downward against the stop 15, moving the wire *x* out of the path of the damper-wires, said dampers being at once thrown into engage-

ment with the vibrating wires by their springs *k*.

By disposing my improved pedal-action below the dampers the parts may readily be reached for adjustment and the cost of construction is greatly lessened, the hammer-action being in no manner interfered with thereby, as frequently occurs in devices of this character of ordinary construction.

Having thus explained my invention, what I claim is—

In an upright piano, the dampers provided with eccentric projections, as *p*, at their lower

ends, in combination with a pedal-actuated crank-rod disposed in the piano-frame below 15 said dampers and provided with arms non-radial to the arc of the crank-arms, and a strip of flexible or rigid material connecting the outer ends of said arms in position to be thrown into engagement with said projections 20 when the dampers are moved by the piano-action, substantially as described.

FRANZ HAMMERLE.
